Inventor

Albert O. Schramm,

By Rupprey & Sonsland,
His Attorney.

UNITED STATES PATENT OFFICE

ALBERT O. SCHRAMM, OF ST. LOUIS, MISSOURI, ASSIGNOR, BY MESNE ASSIGNMENTS, TO THE AMERICAN LAUNDRY MACHINERY COMPANY, OF CINCINNATI, OHIO, A CORPORATION OF OHIO

APPARATUS FOR STRETCHING AND DRYING LAUNDERED ARTICLES

Application filed March 3, 1928. Serial No. 258,766.

This invention relates to an apparatus for stretching and drying laundered articles.

The machine or apparatus, the subject matter of my application Serial No. 215,500, filed August 12, 1927, for apparatus for stretching and drying laundered articles, comprises elements for engaging and holding the upper and lower edges of the articles and devices for engaging the vertical edges of the articles. Mechanism is provided for operating the devices that engage the vertical edges of the articles in order to stretch the same.

The present invention comprises an improvement in such a machine and includes elements for engaging the horizontal edges of the articles to be stretched and dried, which elements comprise series of movable parts capable of easy relative longitudinal adjustment as an incident to and in accordance with the longitudinal stretching of the articles by the devices which engage the vertical edges of the articles.

An object of the invention is to provide an improvement in such machines as disclosed in my said co-pending application Serial No. 212,500, whereby the horizontal edges of the articles obtain proper adjustment automatically and as an incident to the operation of the devices engaging the vertical edges of the articles so that the articles will be stretched straight across in every direction and not subjected to undesirable strains.

Another object of the invention is to provide a machine comprising a pair of horizontal bars each supporting a series of longitudinally movable and relatively adjustable carding brushes for engagement with the upper and lower edges of laundered articles to hold the articles stretched vertically, in combination with devices for engaging the vertical edges of laundered articles, and means for operating said devices to stretch the articles on the frame comprising all of the aforesaid elements in the advantageous manner herein disclosed.

Other objects will appear from the following description, reference being made to the accompanying drawings, in which

Fig. 1 is a side elevation of a portion of a

machine embodying the present invention.

Fig. 2 is an enlarged plan view with a part broken out showing one of the horizontal stretching bars.

Fig. 3 is an end view of the stretching bar 55 shown in Fig. 2.

The machine or apparatus in which the present invention is embodied comprises an approximately vertical frame movable longitudinally into and out of a drying cabinet 1. 60 The frame shown comprises an upright end frame member 2, an upper horizontal frame member 3 and a lower horizontal frame member 4. These frame members are connected together in the form of a rigid frame and 65 the frame so constructed is supported on rollers 5 and mounted vertically by a bracket 6 engaging a rail 7.

The machine further comprises a vertical bar 8 supporting a rotative pinion 9 at its 70 upper end meshing with a horizontal rack 10 on the frame member 3 and a rotative pinion 11 at its lower end meshing with a horizontal rack 12 on the frame member 4. As disclosed in my said application Serial No. 75 212,500, for each pinion 9 and 11 the machine comprises a latch bar 13 arranged in longitudinal alignment and having their ends adjacently disposed and provided with adjacent handles 14 arranged in such relationship that both handles may be grasped by one hand at the same time to release the latches 13 simultaneously from the pinions 9 and 11. Actuating springs 15 may be provided to re-engage the latches with the pinions 9 and 11. 80

The machine further comprises a bracket 16 attached to the frame member 2 and supporting a rotative sheave 17 having a ratchet wheel 18 rigid therewith. A pawl 19 pivoted on the bracket 16 is engageable with the ratchet wheel 18 to prevent the same from turning in a direction to permit the stretched article to become loosened. From the sheave 17 a chain or other flexible device 20 extends 90 to connection with the vertical frame member 8. Thus, it is apparent (Fig. 1) that by turning the sheave 17 in a counterclockwise direction the stretching bar 8 will be drawn 95 toward the end of the frame, the pawl 19 rid- 100

ing upon the periphery of the ratchet wheel 18 permitting the ratchet to turn with the sheave and preventing backward or clockwise turning of the sheave and ratchet.

5 The bar 8 supports on its outer face a vertical carding brush 21 for engagement with the vertical edge of a laundered article, it being understood that the opposite vertical edge of such article is held by some similar or other appropriate device, as disclosed in my said co-pending application Serial No. 212,500, so that when the bar 8 is moved laterally by the chain 20 and its connections the laundered article will be stretched.

15 The machine comprises an upper horizontal bar 22 and a lower horizontal stretching bar 23. These bars 22 and 23 are supported by vertical racks, of which one of said racks is shown and designated by 24, the same being 20 rigid on the vertical frame member 2. Both of the bars 22 and 23 are capable of relative vertical movements and adjustments.

25 The present invention comprises devices mounted on these bars 22 and 23 for engaging the upper and lower edges of the laundered articles to hold the articles stretched vertically and to permit lateral stretching of the upper and lower edges of the articles by operation of the stretching bar 8.

30 As shown, each of the bars 22 and 23 has a plate 25 attached to its outer side and extending longitudinally thereof. The plate 25 on each of said bars 22 and 23 has its upper and lower edges formed with rebent portions 26 (Fig. 3) which rebent edges form channels 27. The upper and lower edges of brush blocks 28 engage in the channels 27. I provide a series of such brush blocks upon each of the bars 22 and 23, the combined length of 40 said brush blocks being less than the length of said bars 22 and 23 so that said blocks may be moved toward and away from each other longitudinally along their supports. Abutment screws 29 at the ends of the channels 27 prevent the brush blocks from moving therefrom. The screws 29, however, are removable and replaceable to permit removal and replacement of the brush blocks. Each brush block 28 supports a carding brush 30 engageable with the upper and lower edges, respectively, of the laundered article.

45 In operation of this machine the upper and lower edges of the laundered article are engaged with the carding brushes 30 on the bars 22 and 23, respectively. One of the vertical edges of the laundered article is engaged with a retaining device (not shown) such as that disclosed in my co-pending application Serial No. 212,500, and the other edge is engaged with the carding brush 21. Next, the sheave 20 is turned in a counter-clockwise direction (Fig. 1) by any appropriate device, as by a crank 31, thus moving the bar 8 on which the carding brush 21 is mounted toward the 60 end 2 of the frame. Since the vertical edge of

the laundered article is engaged with said carding brush 21 and the opposite edge of the article is held by some other device (not shown) the laundered article is stretched. Since the brushes 30—28 are easily movable longitudinally and relatively along their supports 22 and 23, the edges of the article are also stretched uniformly with the remaining portion of the article and without dragging the article across the ends of the carding brushes. In this way the laundered articles 70 are easily and uniformly stretched without damaging the surfaces thereof.

75 From the foregoing it will be seen that my invention obtains all of its objects and purposes in a highly efficient, convenient and satisfactory manner and is substantially free from complicated structures. The device may be varied within equivalent limits without departure from the nature and principle 80 of the invention.

85 I claim:—

1. An apparatus for stretching and drying laundered articles comprising an upright end frame member, an upper horizontal frame member and a lower horizontal frame member parallel with said upper member and each having one end in rigid connection with said upright frame member, a vertical stretching bar, gearing connecting the ends of said stretching bar with said upper and lower frame members respectively, means on said stretching bar for engaging a laundered fabric, a pair of horizontal supports between said upper and lower frame members and each having one end connected with said upright frame member, a series of relatively movable devices on one of said supports for engaging one edge of a laundered fabric engaged with said engaging means on said vertical bar, and means on the other horizontal support for engaging the other edge of said fabric.

100 2. An apparatus for stretching and drying laundered articles comprising a bar, means for supporting said bar in different adjusted positions, a plate attached to one side of said bar and having inwardly rebent edges forming channels, a series of brush blocks having their edges engaged in said channels and being movable along said plate, and a carding brush in connection with each of said blocks.

105 3. An apparatus for stretching and drying laundered articles comprising a pair of parallel bars, a series of carding brushes supported for relative longitudinal movements along each of said bars for engagement with marginal portions of a fabric to be stretched and dried, a device for engaging a marginal portion of said fabric at right angles to the marginal portions engaged by said carding brushes, and means for operating said device to stretch the fabric evenly and uniformly 120 across the entire width of the fabric and to move said carding brushes that are engaged 125 130

with stretched marginal portions of said fabric.

4. An apparatus for stretching and drying laundered articles comprising a pair of parallel bars, a series of carding brushes supported for relative longitudinal movements along each of said bars for engagement with marginal portions of a fabric to be stretched and dried, a device for engaging a marginal portion of said fabric at right angles to the marginal portions engaged by said carding brushes, means for operating said device to stretch the fabric evenly and uniformly across the entire width of the fabric and to move said carding brushes that are engaged with stretched marginal portions of said fabric, means for guiding said device in its movements, and elements for engaging parts of said guiding means to hold said device in its different adjustments.

5. An apparatus for stretching and drying laundered fabrics comprising a bar, means for supporting said bar in different adjusted positions, a plate attached to one side of said bar and having inwardly rebent edges forming channels, a series of brush blocks having their edges engaged in said channels and being movable along said plate, abutments limiting movement of said blocks along said plate and being removable to permit removal and replacement of said blocks, a carding brush in connection with each of said blocks for engaging the article to be stretched and dried, a device mounted at an angle with respect to said bar for engaging the article that is engaged with said brushes, and means for operating said device to stretch the article that is engaged with said brushes in the direction of movement of said brushes along said bar.

6. An apparatus for stretching and drying laundered articles comprising a pair of parallel bars, a series of carding brushes supported for relative longitudinal movements along each of said bars for engagement with portions of a fabric to be stretched and dried, a device for engaging a portion of said fabric at right angles to the direction of movement of said brushes along said bars, mechanism for operating said device to stretch the fabric evenly and uniformly and to move said carding brushes that are engaged with stretched portions of said fabric, and a device co-operating with said mechanism to hold said mechanism in any position to which it is operated while said fabric remains stretched by said device.

ALBERT O. SCHRAMM.
